UNITED STATES PATENT OFFICE.

ALVAH WISWALL, OF CINCINNATI, OHIO, ASSIGNOR, BY DIRECT AND MESNE ASSIGNMENTS, TO FREDERICK VOELCKEL, OF SAME PLACE.

ELECTRO-MAGNETIC ALARM.

SPECIFICATION forming part of Letters Patent No. 286,888, dated October 16, 1883.

Application filed July 5, 1883. (No model.)

To all whom it may concern:

Be it known that I, ALVAH WISWALL, of Cincinnati, Hamilton county, Ohio, have invented a new and useful Improvement in Electro-Magnetic Alarms, of which the following is a specification:

My invention relates to the class of devices in which the act of alighting or walking across a particular spot is made known at a distant station by an electro-magnetic alarm.

Using any of the well-known electro-magnetic alarms and the ordinary means of electrical communication, my invention is directed to a novel mechanical device whereby the pressure of the passer's foot is made effective to close or to open the circuit, according to whether a normally-open or normally-closed circuit is employed. This mechanical device consists, essentially, of an india-rubber tube, at one or both ends of which is an expandible sac or bladder, whose inflation by the air driven into it by the pressure of the intruder's foot causes contact of the wire terminals, so as to complete the circuit, and by so doing bring into activity the alarm by any of the familiar modes.

In the accompanying drawings, Figure 1 is a ground plan of a premises provided with my improvement. Figs. 2 and 3 are longitudinal sections of the circuit-maker in its open and closed conditions, respectively. Figs. 4 and 5 are end views of the device shown in Figs. 2 and 3, respectively. Figs. 6 and 7 are longitudinal and transverse sections, respectively, of a modification of my circuit-maker.

A may represent an apartment protected by my device. B B represent india-rubber tubing, preferably closed at one end. The other end of the tubing enters a sac or bladder, C, of india-rubber, oil-silk, or any other suitable flexible impervious material. Likewise secured to said tube end is a metallic sheath, D,

which is in electrical communication with one of the battery-wires E. Also secured to tube B, but insulated from the sheath D, is a metallic spring, F, whose resilience (except when said spring is pressed forcibly outward) maintains it out of contact with the sheath D. Compression upon the tubing B (such as would be made by the foot of a person passing over it) forces air into the sac C, which, expanding the latter, causes it to force the spring F outward, so as to bring it in contact with the sheath D, and by thus completing the circuit to sound the distant alarm.

Variouſ forms of circuit-closers may, obviously, be combined with such tubing and sac. For example, a form may be given to the spring such as shown in Figs. 6 and 7, which show such a form in its closed condition.

The tubing B may be made to assume the undulating form shown or a coiled or other arrangement by a fastening of twine or netting, canvas, or other flexible fabric, or it may remain unattached and be simply laid underneath a carpet or rug or other floor-covering.

When employed in connection with a closed circuit, all the systems of tubing may, if desired, be united in one series, so as to save wire.

I claim as new and of my invention—

In an electric burglar-alarm, the flexible air-tube B, forming a mat, in combination with an expandible sac connected thereto, and a circuit closer or opener having contact-pieces, the sac to act on one of the contact-pieces, as set forth.

In testimony of which invention I hereunto set my hand.

ALVAH WISWALL.
